UNITED STATES PATENT OFFICE.

EDWARD JAMES LEIGHTON, OF BOSTON, MASSACHUSETTS.

STRETCHER FOR BOOTS OR SHOES.

SPECIFICATION forming part of Letters Patent No. 658,790, dated October 2, 1900.

Application filed September 19, 1899. Serial No. 730,991. (No model.)

To all whom it may concern:

Be it known that I, EDWARD JAMES LEIGHTON, a citizen of the United States, residing in Boston, in the county of Suffolk and State of Massachusetts, have invented a certain new and useful Improvement in Stretchers for Boots or Shoes, of which the following is a specification.

The invention relates to the class of stretchers employing a longitudinally-divided last, the two sections of which are hinged together at the rear and caused to separate or diverge by the advance of an interior spreader; and its object is to simplify the construction and increase the efficiency and ease of operation.

The invention consists in certain details of construction of the hinge-joint and in the means for separating the sections, as will be hereinafter fully described.

The accompanying drawings form a part of this specification and show the invention as I have carried it out.

Figure 1 is a side elevation. Fig. 2 is a plan or top view. Fig. 3 is an elevation with one of the sections removed to show the interior. Fig. 4 is an approximately-horizontal section taken on the line 4 4 in Fig. 1, and Fig. 5 is a transverse section on the irregular line 5 5 in Fig. 3.

Similar letters of reference indicate the same parts in all the figures.

The last is in two hollow portions or sections A A', each practically the counterpart of the other, divided along the longitudinal central line a. Each is preferably a thin malleable casting lightened by the ornamental lattice-work A² and having holes a' at the forward outer part to receive and hold the usual bunion-pieces. (Not shown.) On the interior lower face of each at about the mid-length is a lug A³, extending across the line of separation and lapping upon the inner face of the other and serving to hold both sections in about the same plane. The lugs are curved upward slightly to allow the sections to roll a little relatively to each other in coming to a bearing in the shoe, and thus distribute the pressure. At the rear the upper portion is thickened by an interior boss A⁴, and in line with the latter at a lower level is a bracket A⁵, drilled and tapped to receive a screw-pin

C, reaching thereto from the upper face of the section and extending through the boss. At the forward end above and below on the interior of each section are pairs of arms A⁶ 55 A⁷, each pair loosely embracing an end of a short vertical shaft D, carrying a hollow-faced roller D', free to revolve thereon and confined between the arms A⁶ A⁷, each pair of which are bent toward each other by any suitable 60 tool after the roller and shaft are in place and securely inclose the latter.

B is a tubular nut having a laterally-projecting wing B' on each side, slotted, as at b, and receiving each a pin C, above described, 65 the wing lying between the boss A⁴ and bracket A⁵. The slots allow the sections A A' to separate slightly at the rear while allowing the forward portions to swing apart, as required, thus serving, with the screws C, 70 as a loose hinge or shackle, affording sufficient flexibility or play while holding the sections together. The nut extends rearwardly somewhat beyond the rear faces of the sections, which are notched semicircularly at a² 75 for this purpose.

The operating handle or shank E is screw-threaded nearly its entire length to match to the nut and has a T-head E² on the outer end, by which it may be turned, and thus advanced 80 or retracted in the nut. The forward end carries a cone-shaped spreader E', fixed thereon and adapted to force its way between the adjacent faces of the rollers and urge them strongly apart when advanced, thus causing 85 the sections to separate and exert the pressure as required on the interior of a shoe, in which the stretcher is placed.

A rearwardly-extending fin B², lying behind the wings B' on each side, serves to connect 90 the wings strongly to the body of the nut, and also serves the more important function of taking the strain from the pins C when the stretcher is in use. The fins lie close to the inner faces of the sections at the rear and limit the forward movement of each section 95 relatively to the other. The rear faces of the fins are widened, as at B³, to afford a better bearing-face, and the outer corners are rounded to correspond to the adjacent inner surfaces of the sections.

The head E² may be of any preferred form

adapted to be easily grasped by the hand and may be, as shown, adapted to perform additional service in the shoe salesroom.

By notching the sections at the rear and 5 extending the nut through the opening thus formed all the length required for great strength in this part may be secured.

The slots *b* are formed somewhat wider than the thickness of the pins *C*, so as to allow the 10 sections to advance until one or both are in contact with the fin *B*², which then takes the strain of the thrust and relieves the pins.

Frictional resistance to the advance of the 15 spreader is reduced by the rollers *D*', and the cone may therefore be fixed upon the shank, and the liability of breakage or derangement due to a loose connection of cone and shank is avoided.

The extension of the nut rearwardly between 20 the sections affords a long bearing for the threaded shank and also serves to protect the threads from injury by contact with the adjacent edges of the sections.

The forms and proportions of the parts may 25 be varied within wide limits and parts of the invention may be used without the whole. The cone and rollers may be differently disposed and may be employed with other forms of hinge and last. The thickness of the cast 30 shells forming the sections may be varied and the forms modified to suit the conditions of service. Suitably-hollowed sections, of wood or other material, may be substituted for the castings described. I prefer the whole as 35 shown.

I claim—

1. The sections *A*, *A*', the nut *B* and later-

ally-extending wings *B*' thereon having the slots *b*, and the pins *C* carried by said sections and extending through said slots, in 40 combination with the fin *B*² formed on said nut and matching to the interior surfaces of said sections at the rear, and a threaded shank extending through said nut and carrying a spreader adapted to separate said sections, 45 all substantially as and for the purposes herein specified.

2. The sections *A*, *A*' shackled together at the rear to form a split last, a hollow-faced antifriction-roller *D*' and shaft *D* carried in 50 each section, and a lug *A*³ on each extending across the line of separation and lapping upon the inner face of the other, in combination with a nut *B* carried by the sections and a screw-threaded shank *E* adapted to travel in 55 said nut, and a conical spreader *E*' fixed to said shank and received between said rollers, all substantially as herein specified.

3. A shoe-stretcher consisting of two hollow 60 sections shackled together and each formed near its mid-length on the interior lower face with a lug, said lugs extending transversely of and across the line of separation and overlapping each other and curved upwardly to allow the sections to roll relatively to each 65 other in coming to a bearing.

In testimony that I claim the invention above set forth I affix my signature in presence of two witnesses.

EDWARD JAMES LEIGHTON.
